JOHN GROWDER, OF AVOCA, IRELAND.

SWIVEL FOR USE IN WELL-DRILLING.

1,275,018.

Specification of Letters Patent.

Patented Aug. 6, 1916.

Application filed August 17, 1917. Serial No. 186,771.

To all whom it may concern:

Be it known that I, JOHN GROWDER, a subject of the King of Great Britain, and resident of Connary House, Avoca, county 5 Wicklow, Ireland, have invented a certain new and useful Improvement in Swivels for Use in Well-Drilling, of which the following is a specification.

This invention relates to the swivels 10 which, in well-drilling operations, are used to connect the drilling tool with the wire rope by which the tool is raised and lowered in the bore of the well. In such swivels, the lower end of the rope is held in 15 a ferrule or tubular spindle about the axis of which the body of the swivel is freely rotatable, this tubular spindle having an external shoulder which bears upwardly against an internal shoulder in the hollow 20 part of the swivel-body, so that while the swivel-body (and with it the tool) can rotate relatively to the rope and tubular spindle, a pull on the rope will raise the spindle and, consequently, the swivel-body and tool.

As is well known, the wire rope becomes 25 worn, and is liable to break, immediately above the upper extremity of the swivel, so that it is frequently necessary to withdraw from the tubular spindle the piece of rope 30 held therein, and to thereafter make a fresh attachment at a point above the break in the rope. To enable this to be done, the swivel has in some cases been made in a single piece so constructed as to permit of the 35 rope being, when necessary, passed downward throughout the whole length of the swivel-body and out through the screwed socket in which the tool is held; such an arrangement allowing of only a very narrow 40 shoulder being provided on the spindle and swivel-body, and necessitating the use of a relatively long tubular spindle, which results in excessive wear and rapid deterioration 45 of the rope. In other cases the length of the swivel has been divided at a point between the lower end of the tubular spindle and the upper end of the tool-socket, so as to permit the passage of the rope clear through the upper section of the swivel-body 50 when separated from the lower; the two sections being united by a screwed joint. Such a construction necessitates the provision on the swivel-body of two sets of flats for engagement by screw-spanners, and a consequent lengthening of the swivel, whereof the 55 weight is correspondingly increased.

The object of the present invention is to overcome the disadvantages referred to, by providing a swivel the body of which, while capable of being made in a single piece, is 60 so constructed as to avoid the necessity of passing the rope downward throughout the whole length of the swivel-body and out through the tool-socket. For this purpose there is provided in the improved swivel- 65 body, a chamber forming an enlarged downward continuation of the neck-passage in the swivel-body, said chamber having in its side wall an open slot of such length and width as to permit the insertion in and withdrawal from working position, of the shouldered tubular spindle which is directly attached to the rope. In order to prevent the tubular spindle from dropping out of working position in the swivel-body when the 70 tension on the rope is relaxed, a cross-pin may be removably fixed in the swivel-body immediately beneath the lower end of the 75 spindle.

The invention will be described with reference to the accompanying drawings, wherein Figure 1 is a side elevation of the improved swivel, viewed from the slotted side of the chamber in the swivel-body; Fig. 2 is a sectional elevation viewed at right 80 angles to Fig. 1; and Figs. 3 and 4 are cross sections on lines 3—3 and 4—4 respectively of Fig. 1.

The body of the improved swivel has, as usual, a tubular neck *a* at its upper end, a 85 screwed socket *b* for the reception of the drilling tool at its lower end, and flats *c*, *c* above the level of the socket *b* for engagement by a screw-spanner. Between the lower end of the neck *a* and the upper limit 90 of the flats *c*, *c*, the swivel-body is made hollow so as to provide a chamber *d* whose internal diameter (which is greater than that of the neck *a*) corresponds to the external 95 diameter of the enlarged lower end *e* of the 100 tubular spindle *f*. The spindle *f*, when in the working position shown, extends through the neck *a*, a washer *g* being interposed between the internal shoulder *h* within the chamber *d* and the external shoulder *j* on 105 the spindle *f*. The bore of the spindle *f*, within the enlargement *e*, is made conical as usual, as indicated at *k*, so as to prevent the upward withdrawal of the expanded lower end of the rope (not shown).

The wall *m* of the chamber *d* has, at one side, an upright slot *o* of a width to give

passage to the enlargement *e* on the spindle *f*, the length of the chamber *d* and of the slot *o* being sufficient to permit of the spindle *f* being inserted through the slot 5 from outside and passed upward into the working position shown, or lowered from said position and withdrawn through the slot, as may be required, even when the spindle is attached to the unbroken rope.

10 In order that the width of the slot *o* may be kept as small as possible, the enlargement *e* of the spindle, and also the washer *g*, may have their diameter reduced at opposite sides by means of flats cut thereon as indicated 15 at *r*, *r*.

When the swivel is to be attached to the rope, the latter is passed downward through the neck *a* and outward through the slot *o*. The tubular spindle *f*, with the washer *g*, is 20 then threaded over the rope, whose lower end is thereupon expanded and "metaled" into the conical part *k* of the bore of the spindle. The rope can now be pulled upon so as to draw the spindle *f* through the slot 25 *o* into the chamber *b*, and upward in the latter until the washer *g* is arrested by the shoulder *h*; after which the parts are retained in working position by means of a pin *p* which is passed, transversely of the slot *o*, through holes in the walls *m* of the chamber *d* and securely riveted at the ends.

The neck *a* is, as usual, made of reduced

external diameter and provided with annular grooves *s* adapted for engagement by the fishing tools when the swivel is left in the bore of the well in consequence of the rope breaking.

t is a boring-center provided, for convenience in manufacture, at the bottom of the chamber *d*. 40

I claim:

An improved swivel for use in well-drilling to connect the drilling tool with the wire rope by which the tool is raised and lowered, comprising a body having an elongated tubular neck at its upper end, a chamber below its neck, and closed at its lower end, said chamber being of greater diameter than the bore of the neck and having a right-angled shoulder at the junction therewith, and a 45 slot in the side of the chamber, said slot extending from near the upper end of the chamber to the bottom thereof, a tubular spindle having an enlarged lower end and a reduced upper end which is of a length 50 greater than that of the neck of the body and forming a right-angled shoulder at the junction therewith, a washer between the shoulders of the body and spindle, the washer and the enlarged portion of the 55 spindle having their opposing sides flattened, and a cross pin for retaining the spindle in position in the body. 60

JOHN GROWDER.
